PLATE OR SIMILAR ARTICLE

Shigeru Masuda, 2185 Central Road, Apt. C,
Fort Lee, N.J.

Filed Jan. 8, 1965, Ser. No. 83,347

Term of patent 14 years

(Cl. D44—15)

The figure is a plan view of a plate or similar article, showing my new design, a portion of the design being shown between dotted lines and a repeat portion being shown between dot-and-dash lines.

The plate is of a conventional configuration when viewed from the side and bottom thereof.

I claim:

The ornamental design for a plate or similar article, substantially as shown and described.
